UNITED STATES PATENT OFFICE.

BERTRAM NEILL, OF NORWALK, CALIFORNIA.

GAS AND OIL SEPARATOR.

Application filed October 12, 1922. Serial No. 594,181.

To all whom it may concern:

Be it known that I, BERTRAM NEILL, a citizen of the United States, residing at Norwalk, in the county of Orange and State of California, have invented new and useful Improvements in Gas and Oil Separators, of which the following is a specification.

This invention relates to apparatus for the automatic and continuous separation of water and sand, and gas and oil as the raw product comes from the oil well.

It is an object of the invention to provide an extremely simple, substantial and practical apparatus operative to handle a large volume of crude oil and well product, and to provide a structure capable of being manufactured in comparatively small sizes relative to the capacity thereof.

Another object of the invention is to provide an oil and gas separator having, in combination, telescoping means to facilitate the removal of vaporous oil product from the drier and lighter gases.

Another object of the invention is to provide an oil and gas separator having independently operative oil and gas outlet valves and to provide means for automatically holding the valves each in open position concurrently. In this connection, it is also an object to provide an automatically acting means for closing the gas outlet valve upon accumulation of an excess of oil in the apparatus without affecting the position of the open oil outlet valve, and conversely, it is an object to provide for the closing of the oil outlet valve in event of shortage of oil in the apparatus without closing the gas outlet valve.

Other objects and advantages will be made manifest in the following specification of an embodiment of the invention illustrated in the accompanying drawings, wherein—

Figure 1 is a side elevation of the apparatus, parts of the same being broken away.

Fig. 2 is a side elevation and vertical central section in a plane at right angles to the plane of Fig. 1.

Fig. 3 is a cross section on line 3—3 of Fig. 1.

Fig. 4 is a detail sectional view of the outlet valve rod bushing.

Fig. 5 is a detail sectional view of the telescopic valve rod joint.

Fig. 6 is a sectional detail of the gas scrubbing ring.

The apparatus, as shown in the present embodiment, includes a substantial exterior shell 2 which, in the present case, is shown as cylindrical, although it may be of other form in cross section. The shell is provided with a head 3 and a bottom 4 and as may be desired at several locations, the shell is provided with handholes 5 to provide for convenient access to the interior of the apparatus.

Leading from the upper portion of the shell is a gas outlet pipe 6 in which is provided a suitable valve 7 controlling the discharge of gas. This valve is provided with a stem 8 connected to a lever 9 which in turn is attached to a gas valve operating rod 10 passing through a bushing 11 in the head 3.

The lower portion of the shell 2 is provided with an oil outlet pipe 12 having a suitable valve 13 provided with a stem 14, and this is connected to a lever 15. The opposite end of this lever is secured to an oil valve rod 16 passing through a bushing 17 in the bottom 4 of the shell.

A feature of the invention consists of a construction whereby the two valves 7 and 13 may be concurrently maintained in open discharging position, and further consists of means for automatically restoring the valves to the open position. To that end I provide spring devices connected to the respective valve elements so as to hold the valves open, and the devices are here shown as leaf springs 18 and 19 which may be suitably secured as to the shell 2, and each is shown as engaging a respective lever 9 and lever 15. These springs are operative to automatically bring the valves 7 and 14 to open position when the parts of the apparatus are in the position shown in Fig. 1.

Means are provided for automatically closing either of the valves without disturbing the other, and such means includes a push rod 20 which is aligned with the valve rods 10—16 and means are provided for allowing play longitudinally of the push rod and to provide for the alternate engagement of the push rod with the contiguous parts of the valve rods 10 and 16. For this purpose telescopic connections are provided between the push rod 20 and the valve rods, and these connections may consist of sleeves 21 attached either to the ends of the push rod or to the adjacent ends of the valve rods 10 and 16; the action being the same in either case.

The sleeves 21 are shown as fastened one to the valve rod 10 and the other to the lower end of the push rod 20. The length of the sleeves is such as to permit of relative movement between the push rod and the valve rods without disengagement respectively, so that these rods are constantly held in alignment.

Oil well product is led to the apparatus through one or more supply connections or pipes 23 which are attached preferably immediately between the top and bottom of the shell. Means are provided for preventing the flow of the well product downwardly into the bottom of the trap shell 2 until after the product has been divided so as to separate out water and sand. In other words, means are provided to prevent the descent of the oil of the well product to the bottom of the trap until it has been treated or depleted of the sand and water and the gas has been substantially separated from the oil. This is accomplished by arranging as here shown, concentrically within the shell 2, an inner wall 24 shown as cylindrical and extending upwardly toward the top of the shell and being suitably fastened therein. The upper portion of the inner wall 24 is shown as perforated at 25, the lower portion being imperforate. A bottom is provided for the concentric space between the inner surface of the shell 2 and the outer surface of the inner wall 24 and this bottom prevents the direct passage of the well product downwardly from the supply pipes 23 which, in the present case, are shown as attached at diametrically opposite sides of the shell.

A feature of the invention is to provide for the separation of the water and sand and the gas before the oil passes to the bottom of the shell, and this is accomplished by providing means for the collection of the water and sand as it enters the shell 2 and before the oil passes through the perforated inner wall 24 and thence to the bottom of the shell. Therefore, the bottom just mentioned for the concentric space about the wall 24 is provided with downwardly convergent portions forming a V-shaped pocket or pockets. The bottom may conveniently be formed as of channel iron 26 secured around the lower portion of the wall 24, the channel iron being bent or formed with downwardly convergent portions 27, Fig. 1. The bottom 26 may have as many of the downwardly convergent portions as desired, in the present case there being V-shaped pockets formed on diametrically opposite sides of the wall 24. This wall may be cut away on its lower end so as to conform to the peripheral outline of the connection therewith of the pocket forming bottom 26. As oil product is supplied to the shell 2, the oil accumulates between the shell and the wall 24 and in the pockets

formed by the bottom 26 and rises in the collecting chamber until it reaches the perforations 25 when the oil begins to pass in through the perforations and down to the bottom of the shell, from which it may flow through the oil outlet 12 as controlled by the valve 13.

Means are provided for draining off such water and sand as may accumulate in the bottom of the pockets in the collecting space, and therefore drain pipe or pipes 28 are attached to the shell contiguous to the bottom of the collecting pockets about the wall 24, and through which pipes the collected sand and water may constantly flow. The drain pipes 28 are provided with control valves 29.

The product from the well may consist of a mixture of oil, gas, sand and water and the heavier latter constituents collect in the separating pockets and drain out through the pipes 28 while the oil rises and passes through the wall 24 and descends to the bottom of the trap where, as the level of the oil rises, it becomes effective upon a valve actuating means. This means consists of a float 30 slidably mounted and guided upon the push rod 20 so that as the oil accumulates to a predetermined high point, as is regulated by an adjustable collar 31 on the push rod 20, the float engages said collar and shifts the push rod upwardly so that the parts become operative on the contiguous socket joint 21 of the gas outlet valve rod 10. This valve rod then serves to rock the lever 9 and close the gas outlet valve 7 without affecting the open oil outlet valve 13. As the gas outlet is restricted, gas gradually accumulates in the top of the chamber and reacting upon the oil forces it with accelerated flow through the open oil outlet. As the oil level falls so that the tappet collar 31 releases the gas valve rod 10, the spring 18 thereof automatically opens the gas outlet valve and the gas then continues to flow from the chamber while oil likewise flows from the oil outlet.

Should the oil fall below a predetermined low level, means are provided to close the oil outlet valve 12 to prevent the blowing out of the gas therethrough. Such means includes a lower tappet collar 32 adjustably secured on the push rod 20 below the float 30. As the oil level reaches the low point, the float 30 engages the tappet collar 32 and this causes the downward movement of the push rod 20 and overcomes the spring 19 so that the discharge valve rod 16 is actuated to close the oil outlet valve 13 or to restrict the flow of oil therethrough. After the restriction of the discharge, the oil supply is replenished in the shell 2 and the float is lifted again so that the spring 19 automatically opens the oil outlet valve 13 and normal operation is resumed during

which the float 30 will rise or fall with variations of oil level according to supply conditions.

It is desirable that means be provided for 5 scrubbing the ascending gas so as to recover as much as possible of the vaporous constituents and return the same to the oil trap, and this is accomplished by arranging a pervious barrier in the path of the ascending 10 vapors and gas. Such a barrier may consist of a layer of granular material 35 such as coke which may be supported upon a perforated shelf or rim 36 which further has the function of connecting the upper end 15 of the wall 24 to the shell 2. Above the first separating or scrubbing layer 35, there is a horizontal partition of granular material, such as coke or other desirable substance 37, extending as a diaphragm entirely 20 across the upper portion of the shell. This diaphragm may be supported on a perforated or foraminous basin 38 of downwardly concaved form so as to facilitate draining of the collected liquid centrally of the apparatus 25 and therefore discharged to the interior of the separating chamber.

Further embodiments, modifications and changes may be resorted to within the spirit of the invention as here claimed.

30 What is claimed is:

1. In an apparatus for separating liquids from gas, the combination of a shell having an inlet port for well product to be treated, outlet means for oil, separate outlet means 35 for heavier constituents such as sand and water in the product, an outlet for the gas in the product, and independent self-opening valves exterior of the shell for controlling the oil outlet and the gas outlet, and means 40 in the shell for automatically closing the valves.

2. In an apparatus for separating liquids from gas, the combination of a shell having an inlet port for well product to be treated, outlet means for oil, separate outlet means 45 for heavier constituents such as sand and water in the product, an outlet for the gas in the product, independent self-opening valves controlling the oil outlet and the gas outlet, and means automatically operative 50 by variations of the level of oil in the shell for closing either the oil outlet valve or the gas outlet valve independently of the other.

3. In an apparatus for separating liquids 55 from gas, the combination of a shell having an inlet port for well product to be treated, outlet means for oil, separate outlet means for heavier constituents such as sand and water in the product, an outlet for the gas in 60 the product, self-opening valves controlling the oil outlet and the gas outlet, and an inner wall spaced from the shell and forming therewith a product receiving preliminary settling chamber, the bottom of which 65 is provided with settling zones for sand and

water in the product and into which the sand and water settles from the oil before the oil passes to the bottom of the shell.

4. An apparatus for separating well product comprising, in combination, an outer 70 shell and an inner wall forming therewith a preliminary settling space having a bottom disposed above the bottom of the shell; the inner wall providing for the passage of the oil at a point above the settling space, to 75 the bottom of the shell, an outlet for oil at the lower portion of the shell, an outlet for gas at the upper portion of the shell, and means for draining away water and sand collecting in the settling space. 80

5. An apparatus for separating well product comprising, in combination, an outer shell and an inner wall forming therewith a preliminary settling space having a bottom disposed above the bottom of the shell; the 85 inner wall providing for the passage of the oil at a point above the settling space, to the bottom of the shell, an outlet for oil at the lower portion of the shell, an outlet for gas at the upper portion of the shell, means for 90 draining away water and sand collecting in the settling space, and self-opening valves in the oil and gas outlets.

6. An apparatus for separating well product comprising, in combination, an outer 95 shell and an inner wall forming therewith a preliminary settling space having a bottom disposed above the bottom of the shell; the inner wall providing for the passage of the oil at a point above the settling space, to the 100 bottom of the shell, an outlet for oil at the lower portion of the shell, an outlet for gas at the upper portion of the shell, means for draining away water and sand collecting in the settling space, self-opening valves in the 105 oil and gas outlets, and means for automatically closing the open gas valve as oil level rises in the shell and for automatically closing the oil outlet valve as the oil falls to a predetermined degree in the shell. 110

7. An apparatus for separating well product comprising, in combination, an outer shell and an inner wall forming therewith a preliminary settling space having a bottom disposed above the bottom of the shell; the 115 inner wall providing for the passage of the oil at a point above the settling space, to the bottom of the shell, an outlet for oil at the lower portion of the shell, an outlet for gas at the upper portion of the shell, means for 120 draining away water and sand collecting in the settling space, self-opening valves in the oil and gas outlets, and means for automatically closing the open gas valve as oil level rises in the shell and for automatically closing the oil outlet valve as the oil falls to a predetermined degree in the shell, the automatic means operating one of the valves 125 without concurrent action of the other.

8. An apparatus for separating well prod- 130

- uct comprising, in combination, a receiving shell into which the product is fed, an oil outlet for the shell, a gas outlet, normally open valves in each of said outlets, means 5 normally tending to keep the valves open, and automatically acting means operative in an ascending movement to close the gas outlet valve and in a descending movement to close the oil outlet valve.
10. 9. An apparatus for separating well product comprising, in combination, a receiving shell into which the product is fed, an oil outlet for the shell, a gas outlet, normally open valves in each of said outlets, said 15 valves being independent, and automatically acting means operative in an ascending movement to close the gas outlet valve and in a descending movement to close the oil outlet valve, said means actuating either 20 valve independently of the other.
10. An apparatus for separating well product comprising, in combination, a receiving shell into which the product is fed, an oil outlet for the shell, a gas outlet, normally open valves in each of said outlets, said 25 valves being independent, automatically acting means operative in an ascending movement to close the gas outlet valve and in a descending movement to close the oil outlet valve, said means actuating either 30 valve independently of the other, and means operative to normally maintain the valves in open position.
11. An apparatus for separating sand, water, oil and gas in well products comprising, in combination, a receiving shell, an inner wall spaced from the shell to provide a 35 preliminary settling space thereabout, said
- inner wall being perforated and providing for the passage of oil to the bottom of the shell after the water and oil have settled in the settling space, oil and gas outlets, and means for draining away the settled water and sand.
12. In an apparatus for continuously and automatically separating constituents in oil well product, said apparatus comprising a receiving shell, a settling chamber in said shell wherein water and sand may settle out of the well product, an oil receiving compartment having an oil outlet, gas outlet means at the head of the shell, outlet valves for the gas and oil outlets, the said valves being arranged exterior of the shell, and means within the shell and including valve actuating rods passing through the top and bottom ends of the shell, and an actuator movable in the shell and adapted to operate said rods independently.
13. An apparatus for separating well product comprising, in combination, a receiving shell into which the product is fed, an oil outlet for the shell, a gas outlet, normally open valves in each of said outlets, said 60 valves being independent, automatically acting means operative in an ascending movement to close the gas outlet valve and in a descending movement to close the oil outlet valve, said means actuating either 65 valve independently of the other, and means for normally maintaining the valves in open position.

In testimony whereof I have signed my name to this specification.

BERTRAM NEILL.
